UNITED STATES PATENT OFFICE.

ENOCH RICHARDSON, OF HAWTHORN, VICTORIA, AUSTRALIA.

PISTON-VALVE.

No. 818,976.

Specification of Letters Patent.

Patented April 24, 1906.

Application filed February 27, 1905. Serial No. 247,610.

To all whom it may concern:

Be it known that I, ENOCH RICHARDSON, engineer, a subject of the King of Great Britain, residing at 9 Creswick street, in the city 5 of Hawthorn, in the county of Bourke, in the State of Victoria, in the Commonwealth of Australia, have invented certain new and useful Improvements in Separately-Actuated Exhaust Piston-Valves for Steam and other 10 Engines, of which the following is a specification.

The objects of the invention are as follows:

My invention relates to improvements in valves for steam and other motive engines, 15 and has for its object the construction of a system of three piston-valves working in a cylindrical valve-chest. Two of the said valves are keyed on the same rod, their sole use being to control the admission of steam to 20 the cylinder, and are designated the "steam-valves." Their position on the valve-rod is so adjusted that the inlet steam-passage from valve-chest to cylinder is direct and short, as shown at P, Figure 1. The third piston- 25 valve works in the same cylindrical valve-chest, but is attached to and operated by a separate rod and worked by a separate eccentric. The said third piston-valve works between the two steam-valves and deals with 30 the exhaust-steam only. It is designated the "exhaust-valve" and is so operated that the steam used in propelling the piston to the end of its stroke is released immediately its work is done through the port P, exhaust-passage 35 S, and openings R, Fig. 1.

In order that my invention may be clearly set forth, reference may be had to the accompanying sheets of drawings, in which—

Fig. 1 is a longitudinal section through 40 main cylinder A and cylindrical valve-chest D on line 1 1 of Fig. 2, showing the arrangement of exhaust and steam ports. Fig. 2 is a transverse section through main cylinder and cylindrical valve-chest on line 2 2 of Fig. 45 1, showing the position of steam-inlets M and exhaust-outlet N. Fig. 3 is a longitudinal section of cylindrical valve-chest D, showing the three piston-valves E, E', and G, steam-passages O, and inlet M. Fig. 4 is an external plan view of main cylinder A and cylindrical steam-chest D. Fig. 5 is a front elevation of the inner steam-valve E'; Fig. 6, a front elevation of outer steam-valve E. Fig. 7 is a similar view of the exhaust-valve G. 50 55 In constructing a system of valves according to my invention I employ a cylindrical

valve-chest D, attached to main cylinder A, fitted with piston B and rod C, as generally used. The said cylindrical valve-chest is provided with a steel cylindrical lining Q, within 60 which the steam-valves E, E', and exhaust-valve G work and through which the continuation of steam-ports O and P, Fig. 3, and exhaust-ports R, Fig. 1, are cut. The area of inner steam-valve E' being reduced by the 65 intersection of two rods, it is increased in diameter in order that its area may be the same as the outer steam-valve E, which is without projecting rods. The two steam-valves E and E' are worked by the same rod F, to 70 which both are keyed. The said rod works in the gland f. The exhaust-valve G is operated by a separate rod H, to which it is attached, as shown in Fig. 1. The said rod passes through the inner steam-valve E' and 75 works within a "sleeve" J. The gland L, with stuffing-box K, prevents the escape of exhaust-steam from the middle portion of cylindrical valve-chest D through the steam-valve E', to which the said sleeve is attached. 80 It works through the gland h. The steam-valves E, E' and exhaust-valve G are formed by the use of two disks recessed on the periphery and fitted with cut rings of the form shown in Fig. 1. The exhaust-valve seat I 85 is formed in the steel lining Q by cutting out two circular openings R, intersected by cross-bars, as shown in Fig. 1.

The steam-valves E and E' are worked by the ordinary eccentrics. The exhaust-valve 90 G is worked by a single movable eccentric. As these eccentrics are of the ordinary kind and form no part of the invention, they are not shown in the drawings.

The manner of working is as follows: The 95 piston B being placed at the end of its stroke, as shown in Fig. 1, steam is admitted from the cylindrical steam-chest D through the port P to cylinder A between the piston-head and outer-cylinder cover. As the piston 100 moves backward the piston-valves E and E' are simultaneously moved in the same direction until the action of the eccentrics reverses the motion of said piston-valves, when the supply of steam is cut off by valve E at such 105 point as may have been determined. While the piston B is moving backward, as above described, the exhaust-valve G is brought to the end of its stroke by the action of its eccentric, its motion being then reversed, so that 110 by the time the piston reaches the inner end of cylinder A the exhaust-port R is open for

the release of steam, the eccentric working of the said exhaust-valve G being then almost at its maximum throw. The eccentric working of the exhaust-valve G may be so set that 5 shortly before the piston B reaches the end of its stroke the exhaust-port P is open to the extent shown at R, Fig. 1.

I do not comprise in my invention any particular form of eccentrics for working the 10 steam-valves E and E' nor of the exhaust-eccentric V for working the exhaust-valve G.

Having now described my invention, what I claim as new, and desire to secure by Letters Patent, is—

15 In combination with a cylinder and its piston, a steam-chest of varying interior diameters having inlet and exhaust ports to the cylinder, piston-valves E E' located at each end of the steam-chest, and controlling the inlet-ports, a piston-valve G located between the 20 valves E E' and controlling the exhaust-port,

the valve E being of smaller diameter than pistons E and G, means for moving the valves E E' in unison said means comprising a rod passing through the three valves, valves E 25 and E' being rigidly secured to said rod and valve G having movement thereon, a sleeve J connected to the valve E' and extending through the steam-chest, a packing-box at the outer end of said sleeve, a rod connected 30 to the exhaust-valve G and extending through the valve E' and the sleeve J and its packing-box and means for reciprocating said rod so as to move the valve G independently of the valves E E'.

35 In witness whereof I have hereunto set my hand in presence of two witnesses.

ENOCH RICHARDSON.
